UNITED STATES PATENT OFFICE

2,613,074

APPARATUS FOR SHOWERING MOLTEN METALS

Stephen Esslemont Woods, Bristol, England, assignor to The National Smelting Company Limited, London, England

Application January 24, 1950, Serial No. 140,281
In Great Britain February 7, 1949

9 Claims. (Cl. 266—15)

1

This invention relates to apparatus for showering a molten metal, of the type disclosed in Patents 2,457,544 and 2,473,304, comprising a chamber containing a pool of the liquid metal and a mechanically operated element, such as a rotor bearing vanes, buckets, corrugations or a helical surface, or an oscillating paddle or the like, enclosed in the chamber and dipping into the molten metal.

Such an apparatus may be used for the condensation of metals, such as zinc, by means of the shower or spray of molten metal, which may therefore conveniently be referred to in this context as the "coolant."

In an apparatus of this kind means must be provided for sealing the glands in the chamber through which the rotary or oscillating motion-transmitting shaft of the rotor or other showering element passes.

Methods hitherto proposed and used for sealing such glands have made use of devices intended to prevent liquid metal from reaching the glands. In one example the shaft is provided with sleeves designed to catch and deflect back into the chamber any liquid metal splashed on them or on the shaft with which they are associated. In another proposal a slow stream of gas is forced through the glands from the exterior to the interior of the chamber.

Methods hitherto employed, such as those mentioned above, have not been entirely satisfactory. The above-mentioned sleeves have failed to prevent the permeation or passage of metallic vapor or liquid from the interior of the chamber and liquid metal has been found to solidify upon the working surface of the gland. When cold gas from the exterior has been forced through the gland similar solidification has usually occurred, and heated gas when similarly employed tends to cause decomposition in the gland and the conduits leading thereto and to deposit undesirable substances therein, such as carbon.

The invention consists of a gland sealing arrangement for a metal showering apparatus comprising a gland, a shaft passing through the gland with a substantially unimpeded annular clearance therebetween, means for feeding liquid metal to one end of the clearance to close the clearance and means for collecting the liquid metal escaping from the other end of the clearance.

The sleeve may be made of silicon carbide or graphite.

Preferably the clearance is wider at the end to which liquid metal is fed and narrower at

2

the end from which it escapes back to the chamber.

The invention will be further described with reference to the embodiments shown in the accompanying drawings.

Figure 1 is a vertical section of a splash condenser embodying a horizontal rotor.

Figure 2 is a vertical section of a splash condenser embodying a vertical rotor.

Figure 3 is a section on the line 3—3 of Figure 2.

In the embodiment shown in Figure 1 the rotor 1 is carried by a water cooled metal shaft 2. Where the shaft passes through the side walls 3 of the condenser a sleeve 4 of graphite or silicon carbide is cemented to the shaft. Secured in the side walls 3 surrounding the sleeves 4 are gland rings 5 in which the sleeves are a loose fit, the inside of the gland ring tapering towards the outside of the condenser. Thus at the inner wall of the condenser there may be a clearance of one inch which tapers to a quarter inch at the outside.

The shaft 2 itself may be of iron or steel and may be hollow enabling it to be water-cooled. The rotor 1 itself may be of graphite, silicon carbide or other suitable refractory material and be keyed to a cement sleeve surrounding the shaft, to which it is keyed by splines formed on the shaft. The cement sleeve preferably extends into the gland 5 and supports the sleeve thereof, which may be keyed to the cement sleeve in the same way as the rotor, and may be formed integral with the rotor, if the latter is of the same material as the sleeve. The shaft is rotatably supported in external bearings 8.

Liquid metal is fed to the inner end of the clearance between the sleeve 4 and gland 5 by splash action alone and escapes from the outer end of the gland to the trough 6, returning to the interior of the condenser through a drowned opening 7.

Possible alternative materials to sillimanite for the ring or gland are silicon carbide or fused alumina but the latter is not recommended when zinc is the liquid metal owing to the possibility of reaction to form zinc aluminate. The main requirement for an alternative material is that the material be a refractory which does not contain iron in a form liable to catalyze the decomposition of carbon monoxide and cause deposition of carbon, since in the majority of the applications envisaged the gas in the chamber is largely composed of carbon monoxide. Fireclay may be used although it contains iron, provided it is well

fired at a high temperature, when its iron content becomes inactive as a catalyst for decomposing carbon monoxide.

In the embodiment of Figures 2 and 3 the condensing chamber is laterally defined by four walls, 11, 12, 13 and 14. In the centre of the roof 15 is a square opening 16 bounded on the sides by four walls of which two are denoted by 17 and 18. Except for a circular portion in the centre, the bottom of this opening is defined by a ledge marked 19. Through the hole defined by the ledge 19 passes a shaft 20, covered by a sleeve 21 of silicon carbide or graphite, which carries the rotor 22. A refractory gland ring 23 extends down from the rim of the ledge 19. At a level just above that of the ledge 19 are two refractory troughs, 24 and 25, extending along two of the side walls, 11 and 12 respectively, of the condenser. At right-angles to and connected with the centre of trough 24 is a trough 26 which leads through an opening 27 in the wall 17. Similarly trough 25 is connected by trough 28 to an opening 29 in wall 18. Some of the metal splashed up by the rotor 22 falls into troughs 24 and 25 and by this means is conducted to the ledge 19 where it forms a reservoir for feeding metal down through the gland which is the space 30 between the sleeve 21 and the gland ring 23. The shaft 20 of the rotor is cooled by water which is introduced through pipe 31.

When the apparatus is started up liquid metal flows freely through the gland and keeps it sealed, but after a time the flow may cease, the gland clearance having become choked with a solid deposit. When the liquid metal is zinc, such a deposit consisting mainly of zinc oxide is formed and acts in the manner of a line or bushing, on which the silicon carbide sleeve carried by the shaft rubs but with little friction, the gland clearance being completely filled by the deposit.

If the liquid metal is lead the flow is continuous, little or no deposit being formed and the gland clearance being filled and sealed with liquid metal. In this case application of heat to the gland by means of conveniently placed burners 9 is advisable in order to maintain the fluidity of the metal flowing through the gland.

The clearance tapering in the direction of flow of the liquid metal enables a continuous flow of liquid metal through the gland to be maintained, or a coherent mass of solid deposit to form in the gland and act as a bushing providing an effective seal, while permitting the shaft to rotate freely.

I claim:

1. An apparatus for showering a molten metal comprising a chamber containing a pool of the liquid metal, a mechanically operated metal showering element enclosed in the chamber and dipping into the molten metal, a wall of the chamber, a shaft for operating said element which shaft is supported outside the chamber and extends through an aperture in the wall of the chamber to make connection with the element, a sleeve fixed to the shaft, said sleeve being of material selected from the group consisting of silicon carbide and graphite, a gland of refractory material which does not contain iron in a form liable to catalyze the decomposition of carbon monoxide and cause deposition

5 of carbon, said gland being fixed to the wall of the chamber and surrounding the shaft sleeve with a substantially unimpeded annular clearance therebetween, said metal showering element feeding liquid metal from the chamber to one end of the clearance to close the clearance and flow metal therethrough, and means for collecting the liquid metal escaping from the other end of the clearance.

10 2. An arrangement as claimed in claim 1 in which the gland is made of sillimanite.

3. An arrangement as claimed in claim 1 in which the gland is made of silicon carbide.

15 4. An apparatus for showering a molten metal comprising a chamber containing a pool of the liquid metal, a mechanically operated metal showering element enclosed in the chamber and dipping into the molten metal, a wall of the chamber a shaft for operating said element, which shaft is supported outside the chamber and extends through an aperture in the wall of the chamber with a substantially unimpeded annular clearance therebetween to make connection with the element, said metal showering element feeding liquid metal from the chamber to one end of the clearance to close the clearance and flow metal therethrough, and means for collecting the liquid metal escaping from the other end of the clearance.

20 5. A gland sealing arrangement for a metal showering apparatus comprising a gland, a shaft passing through the gland with a substantially unimpeded annular clearance therebetween, metal showering means secured to the shaft which feed liquid metal to one end of the clearance to close the clearance and flow metal therethrough, and means for collecting the liquid metal escaping from the other end of the clearance, said shaft being rotatably mounted in an external bearing.

30 6. An arrangement as claimed in claim 5 in which the clearance is wider at the end to which liquid metal is fed than at the end from which it escapes.

7. An arrangement as claimed in claim 6 in which the clearance tapers.

8. An arrangement as claimed in claim 5 comprising means for heating the gland.

9. A gland sealing arrangement for a metal showering apparatus comprising a gland, a vertical shaft passing through the gland with a clearance therebetween, a reservoir for feeding metal down through the gland, metal showering means secured to the shaft, and a trough for collecting part of the metal showered by the 35 metal showering means and conducting it to the reservoir.
